UNITED STATES PATENT OFFICE.

CHARLES L. HATHAWAY, OF DENVER, COLORADO, ASSIGNOR TO THE C. L. HATHAWAY ROCK CRUSHER COMPANY, OF DENVER, COLORADO, A CORPORATION OF COLORADO.

GYRATORY CRUSHER.

No. 895,634.

Specification of Letters Patent.

Patented Aug. 11, 1908.

Application filed January 14, 1907. Serial No. 352,270.

To all whom it may concern:

Be it known that I, CHARLES L. HATHAWAY, a citizen of the United States of America, residing at Denver, in the county of Denver and State of Colorado, have invented certain new and useful Improvements in Gyratory Crushers, of which the following is a specification.

My invention relates to improvements in gyratory crushers and more particularly to the class of crushers described and shown in the applications for United States patents, Serial Numbers 309,672 and 309,673 filed by me April 3, 1906.

The object of the present invention is to provide a device of the class named which being composed of a minimum number of parts, is simple and inexpensive in construction and which, having all its working parts supported upon the base or bed plate, is absolutely self contained.

Further advantages derived from the construction of my device will be brought out in the following description, reference being had to the accompanying drawings in the various views of which like parts are similarly designated and in which

Figure 1—represents a vertical section through the device, Fig. 2—a plan view thereof, Fig. 3—a horizontal section taken along a line 3—3, Fig. 1, Fig. 4—a perspective view of the apparatus, drawn to a reduced scale, Fig. 5—an enlarged fragmentary view of the upper portion of the step-box and the therein supported shaft, showing the flexible dust-proof cap employed to protect the bearing against pulverous particles of the rock discharged from the hopper, and Fig. 6—a horizontal section taken along a line 6—6, Fig. 5.

In the drawings 5 designates the bed or base of the device which in practice, is mounted upon a suitable foundation, and which comprises a bottom plate 6 and four superposed plates 7, which extending in a plane parallel to the bottom plate and at equal distances from its center, are connected therewith by integral, webbed standards 8. The base is furthermore provided with a central, hollow cylindrical body 9 which extending above and below the bottom plate 6, is bored to receive the diametrically corresponding, vertically adjustable step 10 which, in practice, supports the upright, gyrating shaft 12.

Mounted upon the plates 7 is the inverted, conically shaped shell or mortar 13, in which the material under treatment is, in practice, comminuted and which is provided with four pairs of laterally extending flanges 14 and 15, the members of which are respectively arranged in horizontal planes with the upper and lower edges of the shell and connected by integral, interposed webs 16. The lower flanges 15 of the mortar are in practice, placed upon the upper surface of the plates 7 on the base, to which they are secured by means of bolts 17, while two opposite flanges 14 on the upper edge of the mortar, support the upwardly extending, diverging standards 18 which are held in place thereon by bolts 19. The mortar is furthermore provided with an interior lining 16, made of hardened metal and preferably composed of a plurality of adjoining sections or so-called "concaves" to facilitate adjustment and renewal. Standards 18 are arcual in cross section to conform with the circular upper edge or mouth of the mortar with which their inner surface is flush and are provided at their upper and lower extremities with laterally ranging parallel cheeks 20 connected by a vertically extending web 21.

A conical hopper 45, the lower edge of which engages the upper edge of the mortar, is secured to the standards which extend along its outer surface and is furthermore reinforced and secured by two angular brackets 40 which are bolted upon the other two flanges 14 of the mortar.

Rigidly secured upon the standards is the centrally disposed cylindrical boxing 22, the diametrically opposite, outwardly extending arms 23 of which are secured upon the uppermost cheeks 20 by means of bolts 24.

Arranged upon the outer extremities of the arms are the axially alined journal boxes 25 which, in practice, support a counter shaft 26 having loose and fixed pulleys 27 and 28 for the usual purpose and a bevel-pinion 29 which meshes into a bevel-gear wheel 30, rotatably mounted in the vertical bore 31 of the cylindrical boxing 22.

The hub 32 of gear 30 which bears upon the upper edge of the box, has a diametrically reduced extension 33 which extending through the bore 31, projects below the boxing and is provided with a collar 34 which engaging the lower edge of the cylindrical body 22, prevents vertical displacement of the gear.

A bushing 35, disposed in a central vertical bore 36 in the gear hub, has an eccentric, obliquely ranging bore 37 through which extends the upper portion of the before named 5 upright shaft 12.

38 designates the conical crushing head which is mounted upon the conically shaped portion 12^a of the shaft inside the mortar 13, and which is surrounded by a correspondingly shaped mantle 39 made of hardened steel and preferably composed of a plurality of adjoining sections to facilitate renewal in ease of wear or breakage.

A conically shaped sleeve 41 surrounding the portion of the shaft inside the hopper 40 in superposed relation to the head, protects the shaft against wear and damage by contact with the continually agitated mass of rock.

20 The crushing head and the superposed sleeve are secured against longitudinal displacement by two nuts 42 and 43, on a threaded portion 12^c of the shaft, the lower one, 42, engaging the upper edge of the sleeve, while the upper one, 43, is split and clamped around the shaft and in engagement with nut 42, by means of a bolt 44. Similarly arranged nuts 45 and 46 are screwed onto the threaded portion 12^d of the shaft in engagement with the collar 34, for the purpose of holding the shaft against longitudinal displacement. A washer 47, composed of fiber or other refractory substance, is preferably interposed between the collar and the upper nut 45 to prevent production of heat by frictional contact of the revolving nut with the collar.

40 The lower extremity of shaft 12 extending into the vertical bore of the central body portion 9 of the base, engages the before mentioned step 10 which is vertically adjustable within the said bore and provided with a wearing plate 48 made of hardened metal, which is let into a recess in its upper surface. 45 The lower extremity of the step, protruding below the cylindrical body 9, engages the upper surface of a follower 49 which is vertically movable along stud-bolts 50, extending downwardly from the said body through corresponding apertures 51. Nuts 52 on the stud bolts are intended to maintain the follower at any desired elevation.

To prevent dust and dirt from reaching the contacting surfaces of the shaft and the wearing plate 48 in the step, the bore in the cylindrical body 9 on the base is provided with a bushing 53 and its mouth closed by means of a cap 54, composed of an annular metal member 55 having a flange 56 extending downwardly from its outer edge, a washer 57 made of rubber or other flexible material, surrounding and engaging the shaft above the member 55, and a ring 58 placed upon the flexible ring and secured to the member 55 by means of a plurality of bolts 59. A cy-

lindrical ring 60 composed of flexible material, is secured by bolts 62 along the inner surface of flange 56 and extending below the lower edge thereof, engages the outer surface of the cylindrical body portion 9. The close contact of the ring 58 with the shaft and of ring 60 with the body 9, effectually excludes all dust and dirt from the step-bearing while the flexibility of the said rings permits the gyratory movement of the shaft, which at 75 this end is slight.

It will be observed that if so desired, the bore of the base above the step box may be filled with oil or other lubricating medium which at any time, during the operation of 80 the device may be introduced therein through a pipe 61 shown in Fig. 1.

Having thus described the mechanical construction of the device, its operation will be readily understood.

85 The rock or ore to be crushed is fed into the hopper 40 from where it passes into the space between the crushing head and the inner surface of the mortar. The gyratory movement of the head imparted thereto by 90 means of the eccentric position of the upper extremity of its shaft in the bushing of the bevel gear wheel 30, gradually crushes the rock until it is reduced to a size sufficiently 95 small to pass through the annular space between the lowermost edges of the head and the mortar.

It will be observed that inasmuch as the greatest movement of the head is at the mouth of the mortar, where it comes in contact with the rock as it is fed into the hopper, the largest pieces will be subjected to the greatest amount of crushing force and that the said force and the size of the fragments of rock are gradually reduced in comparative 100 relation, as the lower end or throat of the mortar is approached. The result is that the matter fed into the hopper passes through the mortar in a continuous stream to be discharged into a suitable subjacent receptacle. The continuous flow of the material is aided 105 by the movement of the crushing head which tends to impel the particles downwardly. Considering that in addition to these features, the crushing force of the device is augmented by the weight of the head and shaft, which in practice may be raised off the step, and that the unobstructed feed openings between the standards permit continuous feeding without danger of clogging or "bridging" 110 of the material, it will be understood that with the device as set forth in the foregoing description the maximum capacity is obtained with the minimum of power, while uniformity of the product is assured.

To alter the size of the product or to compensate for wear of the mantle on the crushing head or of the lining of the mortar, the head may be raised or lowered by vertical adjustment of the step which may be accom- 115

plished without interference with the operation of the machine or the arrangement of its parts.

Having thus described my invention what 5 I claim is:—

1. A gyratory crusher comprising in combination, a base, a superposed shell or mortar, an upright shaft having a conical enlargement within the said shell, its lower extremity engaging the said base, means near its upper extremity to impart a gyratory movement thereto, a crushing head bored to fit the said conical enlargement, a nut for holding the head against vertical movement, 15 and clamping means engaging with the nut to lock the same on the shaft.

2. A gyratory crusher comprising in combination, a base, a superposed shell or mortar, an upright shaft having a crushing element within the said shell, its lower extremity engaging the base, vertically extending standards, a bearing member connecting their upper extremities, means upon the said member to impart a gyratory movement to 20 the shaft, and nuts upon the shaft below the said bearing member, to prevent longitudinal displacement thereof.

3. A gyratory crusher comprising in combination, a base, a superposed shell or mortar, an upright shaft having a crushing element within the said shell, its lower extremity engaging the base, vertically extending standards, a bearing member connecting their upper extremities, a gear wheel revolu- 30

35 bly mounted upon the said member, means coöoperating with said wheel to impart a gy-

ratory movement to the shaft, clamping means upon the shaft below the said hub, and a washer of refractory material interposed between the said hub and the said 40 clamping means.

4. A gyratory crusher comprising in combination, a base having a plurality of superposed plates, a shell or mortar having a plurality of flanges engaging the said plates, and 45 similar flanges on its upper edge, standards upon the latter, a bearing member connecting the said standards, a shaft having a crushing member within the mortar, its lower extremity engaging the base, and means upon 50 the bearing member adapted to impart a gyratory movement to the shaft.

5. A gyratory crusher comprising in combination, a base having a central vertical bored extension, a vertically adjustable step 55 within the bore, a shell or mortar upon the base, an upright shaft having a crushing element within the mortar, its lower extremity engaging the step, means to impart a gyratory motion to the shaft, and a cap comprising an annular rigid member and two annular flexible members connected to the rigid member, one of said flexible members surrounding and engaging the shaft, while the other engages the circumferential surface of the 60 65 said extension of the base.

In testimony whereof I have affixed my signature in presence of two witnesses.

CHARLES L. HATHAWAY.
